INVENTOR,

Jean A. H. Barkey

BY

A. F. Martell

ATTORNEY.

UNITED STATES PATENT OFFICE.

JEAN A. H. BARKEIJ, OF HOLLYWOOD, CALIFORNIA.

REVERSIBLE WRITING PAD.

Application filed August 13, 1924. Serial No. 731,693.

To all whom it may concern:

Be it known that I, JEAN A. H. BARKEIJ, a citizen of Holland, residing at Hollywood, in the county of Los Angeles and ⁵ State of California, have invented new and useful Improvements in Reversible Writing Pads, of which the following is a specification.

My invention relates to improvements in ¹⁰ writing pads and pencil tablets generally used by students, stenographers, etc.

The writing pads and pencil tablets in general use have a back-board permanently attached to one side of the pad or tablet, ¹⁵ so that it is convenient to write on only one side of the sheets thereof, and the other side is left blank or only partially used, thus involving unnecessary waste.

The main object of my invention is to ²⁰ provide a pad of the kind described with a removable back-board, which may be detached from the pad when one side of the sheets have been written on and may be re-attached thereto in such a position that the ²⁵ other side of the sheets may be as conveniently used as the first side, thus not only saving paper but also saving space, in case the pads are to be kept for future reference.

Other objects and advantages will appear ³⁰ hereinafter and while I show herewith and will describe a preferred form of construction, I desire to be understood that I do not confine my invention to such preferred form but that various changes and adaptations may be made therein without departing ³⁵ from the spirit of my invention as hereinafter claimed.

Referring to the drawings which accompany this specification and form a part ⁴⁰ thereof:

Fig. 1 is a view of the front side of the pad.

Fig. 2 is an edge view of the pad shown in Fig. 1.

Fig. 3 is a back view of the pad.

Fig. 4 is an enlarged sectional view of the pad taken on line 4—4 of Fig. 1.

The manner of binding the sheets, in forming the pad, is a part of my invention.

As shown in Fig. 2 the sheets 10 which

form the pad are bound at one end by binding strips 11 of equal width and thickness on both sides of the pad. The sheets may be clamped between these strips by sewing through them, but are preferably held together by clamping staples 12 extending through the pad and binding strips and having their sides 13 bent down in the usual way. Holes 14 are made through the binding strips and pad. ⁵⁵

A back-board 15 having holes 16 in one end, so spaced as to coincide with holes 14 in the pad, is provided and is attached to the pad by means of metal clips 17 having split shanks 18, which extend through holes 14 and 16 and the ends of which are bent outward as at 19 to form a detachable fastener. Clips 17 are made of sufficiently thin and flexible metal so that ends 19 may be straightened out, when the pad is to be ⁷⁰ reversed, the back-board may be detached from the original side of the pad and re-attached to the other side thereof in the same way. With the pad thus reversed the second side of its sheets may be used ⁷⁵ as readily as the first side.

Having thus illustrated and described my invention, I claim:

1. A reversible writing pad, comprising ⁸⁰ a permanent assemblage of sheets of material adapted for writing thereon to form a pad, permanent binding strips on both sides of said pad, clamping one end thereof, and a back-board having one of its ends detachably fixed to said binding strips and ⁸⁵ pad, so that said back-board may be removed from either side of said pad and may be re-attached to the other side thereof.

2. A reversible writing pad, comprising ⁹⁰ a plurality of sheets assembled to form a pad, binding strips fixed to one end of said pad on both sides thereof, permanent clamping staples extending through said pad and binding strips, a back-board having one end detachably fixed to said pad and detachable means for fixing said back-board to said pad, so that said back-board may be removed from one side and fixed to the other side of said pad. ⁹⁵

3. A reversible writing pad comprising ¹⁰⁰

plurality of sheets of paper permanently assembled to form a pad, binding strips extending through the holes in said clamping one end of said pad, clamping staples extending through said pad and binding strips, a back-board having holes through one end thereof adapted to coincide with smaller holes through said pad and binding strips, and detachable fasteners extending through the holes in said back-board, pad and binding strips, so that 10 said back-board may be detached from one side of said pad and re-attached to the other side thereof.

JEAN A. H. BARKELJ.
